UNITED STATES PATENT OFFICE.

HERBERT E. MARKS, OF GLEN OSBORNE, SEWICKLEY, PENNSYLVANIA.

ROOF OR FLOOR CONSTRUCTION.

Application filed December 18, 1922. Serial No. 607,020.

To all whom it may concern:

Be it known that I, HERBERT E. MARKS, a citizen of the United States, and a resident of Glen Osborne, Sewickley, in the county of Allegheny and State of Pennsylvania, have invented a new and useful Improvement in Roof or Floor Constructions, of which the following is a specification.

This invention relates to roof or floor constructions in which the roof deck or floor is formed of cementitious material in the form of slabs, preferably pre-cast, and in which a metal mesh reinforcement, or its equivalent, is embedded in the cementitious material.

The object of the invention is to provide slabs for the purpose stated which cheapen the construction of roofs and floors, which insures that the metal reinforcement can be located well down in the tension zone of the slab but nevertheless completely protected against exposure, which have marked heat insulating properties, thus preventing the ceilings from sweating, and which are permanent waterproof on their upper surface.

In the accompanying drawing Fig. 1 is a plan view, partly broken away, showing the invention applied to a roof construction; Fig. 2 is a vertical sectional view taken on the line 2-2, Fig. 1; and Fig. 3 is a view of a portion of Fig. 2 on enlarged scale, showing the preferred form of metal reinforcement.

The drawings illustrate the invention applied to a roof construction, but it can be applied in any exactly similar way to a floor construction. In the drawings 1 represents the main beams of the structure, which in the case of the roof will be the purlins. 2 These may be of any suitable type, either wood or metal, and are illustrated as metal channel beams. 2 indicates the slabs which are shown of a length equal to the distance between adjacent purlins and are supported at their ends upon the purlins, but which may be of any desired size and supported in any desired way. These slabs are formed of three parts, to-wit, a lower facing portion 3, preferably formed by the well known plaster or gypsum board, a member or body portion 4, formed of a material hereinafter described, and the metal reinforcement 5 embedded in the body 4 near its lower surface and well down in the tension zone of the slab.

The body 4 is formed of a suitable bituminous (bituminous mastic) material, or so-called bitulithic concrete, either artificial, that is, formed by mixing together asphaltum with a suitable aggregate, such as sand, pebbles, or broken stone, in suitable proportions, but which preferably will be the natural rock asphalt found in many parts of the country and which comprises the natural mixture of sand and a small percentage, approximately 10% of asphaltum.

These slabs will be formed in suitable molds, preferably by a cold-pressing operation, although if desired the broken up rock asphalt may be mildly heated before molding. The molding operation will be performed in well known molding ways, by placing in the mold the plaster board, the metal reinforcement, and the bitumastic material in proper relation to each other and then applying pressure to densify the bitumastic material and thoroughly bond the material together. Preferably a thin layer 9 of hot asphalt will be applied between the plaster board and the bitumastic material, in order to secure a stronger bond between the plaster board and the body of the slab. When thoroughly pressed the parts unite so thoroughly as to form substantially an integral slab. The plaster board need not be placed in the bottom of the mold, but the body of bitumastic material first formed therein under pressure and the face of plaster or gypsum formed thereon by pouring the gypsum or concrete upon the body up to the top of the mold, or the plaster board attached to the top of the body by means of the binder, in either case the entire mass being thoroughly bonded together so as to form a substantially monolithic structure.

The metal reinforcement may be of any kind, but is illustrated of a construction shown in and claimed in an application of even date herewith, Serial No. 607,019, and comprising an electrically welded fabric composed of longitudinal or strand wires or rods 6 and transverse wires or rods 7 welded together at their crossing points, and so located in the slab that at one end thereof a transverse wire or rod 7 is outside of and spaced from the end of the slab, while at the opposite end of the slab the longitudinal members 6 project beyond the end thereof a suitable distance, so that when the slabs

are placed in position the projecting ends of the longitudinal members of one slab can be bent for interlocking with the transverse member of the adjacent slab, thus forming 5 a substantially continuous reinforcement for the length or width of the roof or floor. The space between the ends of adjacent slabs will be filled with suitable grouting, preferably bitumastic material, as shown at 10 8, after the projecting ends of the reinforcement are interlocked.

The slab described is per se waterproof and needs no waterproofing coating applied to its top surface. It is substantially a 15 monolithic slab. The plaster on the under surface imparts heat insulating properties to the slab and prevents the ceiling from sweating. In addition, it insures that the metal reinforcement will not be exposed on 20 the lower face of the slab even though said reinforcements be located well down toward the lower surface of the bitumastic body.

The construction described is cheap on account of the cheapness of the material used. 25 which in its preferred form is a natural rock which needs only to be crushed, and needs no heating to mold it into the slab, although a moderate heating may be resorted to, if desired, but will not materially 30 add to the cost. When artificial bitumastic material is employed the percentage of bituminous constituent will be low, approximately that of the natural rock asphalt. The slab is strong, has good weathering properties and because of the low bituminous content forms a very strong compression member with substantially no slippage factor, and this enables the metal reinforcement to effectively strengthen the slab. Its natural 35 waterproofing qualities makes it unnecessary to add the usual waterproofing sur-

facing which is applied to roof decks formed of concrete, gypsum or like material.

In certain relations the construction need not be embodied in pre-cast slabs but can be 45 formed into slabs directly in place.

I claim:

1. A slab for roof or floor constructions comprising a plaster or gypsum board forming its lower face, and a body of bitumastic 50 material molded thereto and integral therewith.

2. A slab for roof or floor constructions comprising a plaster or gypsum board forming its lower face, a body of bitumastic material, and an interposed bituminous bonding 55 layer.

3. A slab for roof or floor constructions comprising a body of bitumastic material, a metal reinforcement embedded in said body 60 in the tension zone thereof, and a lower facing bonded to said body and of a material non-adherent to the mold for forming the slab.

4. A slab for roof or floor constructions 65 comprising a bitumastic body, a metal reinforcement embedded therein and located in its tension zone, a lower facing united to said body by an interposed bituminous bonding layer and of a material non-adher- 70 ent to the mold in which the slab is formed.

5. A slab for roof or floor constructions comprising a plaster or gypsum board forming its lower facing, a bonding coating of bituminous material applied thereto, and a 75 body of bitumastic material molded under pressure to said plaster or gypsum board.

In testimony whereof, I sign my name.

HERBERT E. MARKS.
